(57) **CLAIM**

The ornamental design for a set of exercise equipment, substantially as shown.

DESCRIPTION

FIG. 1 is a front perspective view of a first design of my series relating to exercise equipment;

FIG. 2 is a left-side perspective view thereof;

FIG. 3 is a rear perspective view thereof;

FIG. 4 is a front perspective view of a second design of my series relating to exercise equipment;

FIG. 5 is a left-side perspective view thereof;

FIG. 6 is a rear perspective view thereof;

FIG. 7 is a front perspective view of a third design of my series relating to exercise equipment;

FIG. 8 is a left-side perspective view thereof;

FIG. 9 is a rear perspective view thereof;

FIG. 10 is a front perspective view of a fourth design of my series relating to exercise equipment;

FIG. 11 is a right-side perspective view thereof;

FIG. 12 is a rear perspective view thereof;

FIG. 13 is a front perspective view of a fifth design of my series relating to exercise equipment;

FIG. 14 is a right-side perspective view thereof;

FIG. 15 is a rear perspective view thereof;

FIG. 16 is a front perspective view of a sixth design of my series relating to exercise equipment;

FIG. 17 is a left-side perspective view thereof;

FIG. 18 is a rear perspective view thereof;

FIG. 19 is a front perspective view of a seventh design of my series relating to exercise equipment;

FIG. 20 is a left-side perspective view thereof; and,

FIG. 21 is a rear perspective view thereof.
